UNITED STATES PATENT OFFICE.

HARRY LANGER, OF MILWAUKEE, WISCONSIN.

KNITTING MACHINE.

Application filed January 27, 1923. Serial No. 615,185.

This invention pertains to improvements in full-fashion knitting machines, employed in forming what are commonly known as full-fashioned hose. To produce full-fashioned hose economically the work is divided into two operations, the leg of the stocking being made on a machine called the "legger", while the foot is knitted on another machine called the "footer", and although both the "legger" and "footer" machines are practically identical in design and principle of operation, differing only in minor details, the present invention is particularly designed for most advantageous use in connection with the "legger".

Heretofore there have been numerous attempts in machines of this character, to provide means for cushioning the carrier rods at the end of their movement prior to engagement with their respective stops, and while these devices have been more or less successful in accomplishing this general purpose, it has always been necessary to manually adjust them to compensate for the various lengths of movement of the carrier rods, which are required in the forming of full-fashioned hose. This met with serious objections, due to the fact that an operator on one of these machines was required to manually manipulate various levers for controlling different operations of the machine, and, consequently, failure, resulting from oversight, to adjust the cushioning means, would cause serious damage to the machine. Furthermore, these devices have been more or less complicated and expensive in structure.

It is, therefore, primarily an object of the present invention to overcome the foregoing disadvantages and provide a simple and efficient mechanism for machines of the above character, which mechanism is adapted to retard movement of the carrier rods prior to engagement with their respective stops, thus reducing impact to a minimum and eliminating sudden and excessive jar with resultant wear upon the machine.

Another important object resides in the provision of a cushioning mechanism for the carrier rods, which mechanism performs its function during the various operations of the knitting machine, without necessitating manual control or adjustment.

A still further object resides in the provision of simplified means for imparting movement to the cushioning mechanism,

whereby complicated gearing and transmissions are eliminated.

With the above and other objects in view, which will appear as the description proceeds, the invention resides in the novel construction, combination and arrangement of parts, substantially as hereinafter described and more particularly defined by the appended claims, it being understood that such changes in the precise embodiment of the herein disclosed invention may be made as come within the scope of the claims.

In the accompanying drawings:

Figure 1 is a fragmentary plan view of a conventional type of full-fashion knitting machine, illustrating the present invention attached thereto.

Figure 2 is an elevational view of a portion of a knitting machine illustrating the mechanism for imparting reciprocative movement to certain of the longitudinal rods.

Figure 3 is a transverse, sectional view taken on the line 3-3 of Figure 1.

Figure 4 is a transverse sectional view taken on the line 4-4 of Figure 2.

Figure 5 is a detail view illustrating a modified form of mechanism for reciprocating the cushioning rod.

Figures 6, 7, 8, and 9 are diagrammatic views illustrating various operative positions of the present invention, and

Figure 10 illustrates the fabric formed on the machine.

In illustrating the present invention, the same is shown in connection with the conventional type of full-fashion knitting machine employed in forming the fabric for the leg of a stocking, and comprises a plurality of sections formed between the standards or frames 1, which frames are connected by longitudinal beams 2. In practice, each section is capable of forming two stockings, but for the purpose of simplicity, the machine illustrated is capable of forming only a single stocking to a section.

Mounted on the frames 1 are brackets 3, which are provided with bearings for a friction rod 4 adapted to reciprocate longitudinally and extending throughout the entire length of the machine. Mounted in the brackets 3 adjacent the friction rod 4 is a stationary guide rod 5 which is engaged by the lateral ears 6 projecting from the friction boxes 7 and 8 mounted on the friction rod 4. These boxes are of conventional

structure and are capable of selective operative connection with the carrier rods in the usual manner.

Secured to the top of the frames 1 and extending longitudinally throughout the entire length of the machine is an L-beam 9 which serves to carry various parts of the knitting mechanism, not shown. Secured to the beam 9 at spaced intervals are the brackets 10 in which are mounted a plurality of carrier rods extending longitudinally throughout the length of the machine. In forming the fabric for a stocking, from a single texture of yarn, only two carrier rods are required. Consequently, throughout the drawings and description only two rods 11 and 12 will be referred to. The remaining rods illustrated in Figure 3 of the drawing are employed only where various yarns are used in combination, such as silk, mercerized cotton, etc. The friction box 7 serves to actuate the carrier rod 12 which is only employed in forming the leg L and one of the heel tabs H illustrated in Figure 10, while the friction box 8 is brought into operation to actuate the carrier rod 11 which is employed in forming the opposite heel tab H', which is formed simultaneously and in conjunction with the heel tab H. The carrier rods are provided with the customary yarn carriers Y, which carry yarn back and forth across the needles, not shown, in the usual manner.

As best illustrated in Figure 2 of the drawing, reciprocal movement is transmitted to the friction rod 4 by means of the driven shaft 13 on which is keyed the coulier cam 14, which rotates between the rollers 15 and imparts reciprocal movement to the pitman 16 and consequently to the levers 17 and 18. The lever 18 is pivotally mounted at its lower end in the stationary bearing 19 while its upper end is connected by means of a link 20, to the friction box bracket 21 which is connected to the friction rod 4 and the connecting bar 22, the latter extending throughout the entire length of the machine and carrying the cock boxes 23, provided with conventional slur cocks that engage and push the jacks, not shown, forwardly. The friction box bracket 21 is slidably mounted and guided on the beam 24 which is secured to a pair of the frame members 1.

From the foregoing description it will be seen that as the coulier cam 14 rotates, reciprocal movement is imparted to the pitman 16, the lever 17 merely oscillating in the stationary bracket 25, thus serving to hold one end of the pitman in place, while the other end, which is connected with the lever 18, will cause the same to be oscillated, imparting reciprocal movement to the friction box bracket 21 and thence to the friction rod 4.

All of the foregoing description pertains

to a conventional structure of full-fashion knitting machine and it will, therefore, be understood that no claim is made thereto, other than in combination with the present invention which will be hereinafter described.

As set forth in the preceding objects, the invention consists in a mechanism adapted to retard the movement of the carrier rods prior to the limit of their travel, thus serving to cushion the same and prevent sudden jar, with resultant wear, as the rods contact with their respective stops "S." This is accomplished by the provision of a cushioning rod 26 slidably mounted in bearings formed in the brackets 3 and extending throughout the entire length of the machine adjacent the friction rod 4. Reciprocal movement is imparted to the rod 26 by means of the auxiliary pitman 27, illustrated in Figure 2 which pitman is connected at one end to the lever 28 connected to the stationary bearing 25, while the other end is pivotally connected to the lever 18, thus receiving reciprocal movement. Extending upwardly from the auxiliary pitman 27 is an arm 27' which, by means of the links 29, is connected to the bracket 30 adjustably secured to the cushioning rod 26 and guided on the guide rod 5, thus preventing rotary movement of the cushioning rod in its bearings.

From the foregoing description, it is obvious that reciprocal movement will be imparted to the cushioning rod 26 simultaneously and at a reduced speed to the reciprocal movement of the friction rod 4, due to the fact that the auxiliary pitman 27, which imparts movement to the cushioning rod, is connected to the lever 18 at a point considerably closer to the center than the connection between the lever 18 and the friction rod.

In Figure 5 of the drawings I have illustrated a modified form of mechanism for imparting reciprocal movement to the cushioning rod 26. This differs from the preferred form in that the auxiliary pitman 27 is eliminated and the arm 27' is formed integral with the main pitman 16. It is obvious that the same results will be accomplished by this modified structure, inasmuch as the pitman 16 reciprocates at a slower speed than the end of the lever 18, which is connected to and imparts reciprocal movement to the friction rod 4.

Mounted on the cushioning rod 26, and adjustably secured thereon by means of set screws, are a plurality of stops, 31 32, and 33 provided with lateral extensions which travel on the guide rod 5 and engage the lateral extensions 6 of the friction boxes 7 and 8 for the purpose of retarding movement of the boxes prior to engagement of the carrier rods 11 and 12 with their respective stops "S." Rotatably mounted on the cush-

ioning rod 26 is a dog 34 held against longitudinal movement on the shaft 26 by means of the stop 31 and the retaining collar 35. The dog 34 is normally held in engagement 5 with the guide rod 5 by means of the spring 36 connected to the arm 37 of the dog and the arm 38 extending from the stop 31. Thus it will be seen that during certain operations of the knitting machine the dog is adapted 10 to engage the extension 6 of the friction box 7.

In the operation of the cushioning mechanism, which will be described later, it is necessary at a certain point to raise the dog 34 15 out of the path of travel of the extension 6 of the friction box 7. In order to accomplish this the dog is provided with a depending tail 39, which, during a portion of the travel of the dog, is engaged by a cam projection 20 40 carried by the beam 41 secured to a pair of the brackets 3.

Taking up the operation of the cushioning mechanism, attention is directed to the diagrammatic views illustrated in Figures 6, 7, 25 8, and 9, and to Figure 10, which illustrates the fabric formed on the knitting machine. The first operation of the knitting machine is to form the leg L, which is the greatest 30 width of the stocking, and therefore requires the greatest distance of travel of the yarn carriers Y attached to the carrier rod 12, this rod being the only one employed in forming 35 the leg portion. The length of travel of the yarn carrier in forming the leg width of the fabric is indicated throughout the views by A.

Figure 6 illustrates the cushioning rod 26 and the friction rod 4 traveling in the directions indicated by arrows. Consequently, 40 the friction box 7, which is carried by the friction rod 4, is, also, actuated in that direction, imparting movement to the carrier rod 12 and yarn carriers Y. In the relative position of parts illustrated in Figure 6, 45 the friction box 7 is shown at a point where it engages the dog 34, and inasmuch as the cushioning rod 26 is actuated at a reduced rate of speed to the friction rod 4, it is obvious that further movement of the friction box 7 is retarded and reduced to the speed 50 of travel of the cushioning rod, which is considerably less than that of the friction rod, thus eliminating excessive jar as the carrier rod 12 engages the stop "S."

55 In Figure 7 the cushioning rod and friction rod are shown as traveling in the opposite direction to that illustrated in Figure 6 and the friction box 7 has just engaged the stop 32, thus retarding further movement of the friction box and carrier rod 12 in the direction indicated.

In forming the narrow portion of the fabric the yarn carrier travels the distance indicated by B on Figures 6, 7, and 10, and it is 60 obvious that the same retarding action will

take place, although the length of travel of the yarn carrier after the friction box has been engaged by the stops on the cushioning rod is somewhat reduced.

In forming the heel tab H, the travel of 70 the carrier rod 12 is reduced to the distance indicated by C, and in this operation of the knitting machine the friction box 8 and the carrier rod 11 are brought into operation to form the heel tab H', the carrier rod 11 75 with its yarn carriers travelling a similar distance to the rod 12, as indicated by C in Figures 8 and 9. Due to the reduced traverse of the friction box 7, in forming the heel tab H, and the fact that the cushioning rod 26, with its stops, has the same traverse at all times, it is essential as shown in Figure 8, that the dog 34 be thrown up out of operative position to clear the friction box 80 when the yarn carrier of the rod 12 is stopped at the inner edge of the heel tab, in order that the dog 34, secured on the cushioning rod, may continue its travel to the left and pass the friction box 7 necessarily stopped with the carrier rod 12. The 85 operation of throwing out the stop 34 is automatically accomplished by the cam 40, which eliminates manual operation. On the reverse movement of the rod, as illustrated 90 in Figure 8, the stop 31 is engaged by the friction box 7 and functions in place of the dog 34 due to the fact that the dog has previously moved past the friction box when the carrier rod 12 and yarn carrier were stopped at the inner edge of the left heel tab, and the stop 31 brought to a position 95 closely adjacent the friction box. Obviously the friction box, upon movement to the right, will overtake and engage the stop 31 due to the fact that it travels at a greater speed.

100 Figure 9 also illustrates the function of the stop 33 which is shown at that point of operation where it is engaged by the friction box 8, thus serving to retard movement of the rod 11 prior, in the direction indicated by arrow, to engaging the stop "S."

110 From the foregoing description it will be seen that a very simple, economical and efficient mechanism has been provided which serves to retard the movement of the carrier rods prior to engagement with their respective stops, and by means of the dog and cam for lifting the same at certain intervals, the mechanism is capable of serving 115 its cushioning function throughout the various knitting operations of the machine, the necessity of manual adjustment or setting of the cushioning mechanism being 120 eliminated.

125 I claim:

1. In combination with, a knitting machine including a carrier rod, a friction rod, means for reciprocating said friction rod, and a friction box slidable on said friction rod and operably engaging said carrier rod; 130

1 a cushioning rod, means for reciprocating said cushioning rod simultaneously with and at a reduced speed to said friction rod, a plurality of stops carried by the cushioning rod for engaging said friction box prior to the end of its travel whereby movement of the friction box is retarded, and means for rendering one of the stops inoperative at a certain point in its travel, to permit movement of the cushioning rod after the friction box has been stopped.

2. In combination with, a knitting machine including a carrier rod, a friction rod, means for reciprocating said friction rod, and a friction box slidable on said friction rod and operably engaging said carrier rod; a cushioning rod, means for reciprocating said cushioning rod simultaneously with and at a reduced speed to said friction rod, a pair of stops carried by the cushioning rod adapted to engage said friction box at certain intervals prior to the end of its travel, whereby movement of the friction box is retarded, a pivoted stop also carried by the cushioning rod and adapted to engage the friction box at certain intervals, and means for rendering said pivoted stop inoperative at certain points of its travel, to permit

movement of the cushioning rod after the friction box has been stopped.

3. In combination with a knitting machine including a carrier rod, a friction rod, and a friction box slidable on said friction rod and operably engaging said carrier rod; a cushioning rod, means for reciprocating said cushioning rod simultaneously with and at a reduced speed to said friction rod, a pair of stops carried by the cushioning rod and engageable with said friction box prior to the extremes of its travel, and an additional stop carried by the cushioning rod intermediate said pair of stops for engagement with said friction box during a portion of its intermediate travel, and means for automatically rendering said intermediate stop inoperative at predetermined intervals, to permit movement of the cushioning rod after the friction box has been stopped.

In testimony that I claim the foregoing I have hereunto set my hand at Milwaukee, in the county of Milwaukee and State of Wisconsin.

HARRY LANGER.
